APPARATUS FOR DISPLAYING VARIABLE INFORMATION IN OFFICES AND ELSEWHERE

Raymond A. E. Guichard, Paris, France

Application November 10, 1950, Serial No. 194,982
In France November 19, 1949

7 Claims. (Cl. 35—24)

1

This invention relates to the kind of apparatus for displaying information in a clearly visible manner which is commonly known as a planning system and in which overlapping strips of plastic, cardboard or other material are moved longitudinally in channels on a frame that is usually hung on a wall, but may be mounted on a stand. As an example of the use of such an apparatus, several strips of different colours lying one behind the other in the same channel may by their respective visible lengths indicate the quantities of a given material in stock, on order and reserved for specific purposes. To the extent to which the strips overlap, a strip in front completely conceals one or more behind it. Now as the state of affairs changes one or another strip is moved longitudinally in the channel to change the exposed and visible length of one or more of the strips and often in the apparatus hitherto used an underlying or overlapping strip is accidentally moved at the same time. In any event, the exact position of each strip in the channel is a matter of importance and with the apparatus used hitherto a strip can easily be displaced longitudinally.

In my application Serial No. 48,948, now Patent No. 2,622,346, I have described how this accidental displacement can be prevented by providing interengaging means on the strips and frame by which each strip may be held in a number of alternative positions. Although this is effective in preventing displacement during the adjustment of the strips, it is found that if the apparatus is carried about or shaken the means may disengage so that the apparatus no longer conveys the desired information.

It is an object of this invention to provide means independent of the action of gravity for resisting longitudinal movement of the strips.

It is a further object to urge means on strips and frame resiliently into engagement.

It is a further object to provide locating elements resiliently connected to the strips.

The various preferred embodiments of the invention are shown, by way of example only, in the accompanying drawings. In these drawings:

Figure 1 is a front view and Figure 2 an end elevation of one construction;

Figure 3 shows part of one strip and a spring fixed to it;

Figure 4 is an end elevation of part of an apparatus in which strips as shown in Figure 3 may be used;

Figures 5 and 6 are views similar to Figures 3 and 4 of another strip and apparatus;

2

Figure 7 is a perspective view of a modified form of strip with a spring; and

Figures 8 and 9 are respectively a front view and a plan of yet another strip and spring.

5 In Figures 1 and 2 two strips 2 and 4 are shown overlapping in a channel 6 which is one of several carried on a frame 8. The strips are differently coloured, and the length of the exposed part of each gives a piece of information. One or more strips must be moved longitudinally in the channel when the state of affairs which is visibly indicated changes, and to prevent one strip being accidentally displaced longitudinally while another is positively moved each strip has a forwardly bent tongue 10 constituting a locating element which engages one or another of openings 12 in the front wall of the channel 6. The tongue 10 serves also as a handle by which the strip is disengaged and slid along the channel as required. Accidental disengagement is resisted by a spring 14 carried by the strip and bearing against the bottom of the next channel 6 above. This spring is a wire, fastened at one end to the strip by a rivet 16 and having a rounded free end 18. It will be seen that the spring 14 bears against an abutment which in the construction illustrated is the bottom of the channel 6, but of course may be some other member carried by the frame. As the spring sets up frictional resistance to movement of the strip along the channel, it may, if desired, be used alone to prevent accidental longitudinal displacement of the strip. However it is preferably used as shown in Figures 1 and 2 in conjunction with the tongues 10 and openings 12.

30 Figures 3 and 4 show a strip 20 which carries a spring 30, which is formed of a single bent piece of wire. This wire is secured at one end to the strip by a rivet 28 and is inclined upwardly as shown. It is then bent into a loop 22, and is then bent back and out of the plane of the strip to form a handle 32 by which it and the strip may be moved.

45 This strip slides in a channel 26, the back wall of which extends upwardly and then forwardly as shown at 29 to form a horizontal abutment for the upper end of the inclined part of the springs. The part 29 has a series of openings 24 in it, and the looped part 22 engages in one or another of these and so constitutes a locating element.

50 In the modification shown in Figures 5 and 6 there is a strip with a spring 60 of much the same shape as that in Figures 3 and 4, and the strip slides in a channel 61. In this case, however, the abutment for the spring is constituted

3
by the underside of the next channel 61 above. Openings 62 are made in the bottom of each channel, but, in order to prevent any interference with the strips in the channel above, the springs 60 are formed into loops 63 which are of such a small size that they will engage in but not project through the openings 62.

In the modification shown in Figure 7 the strip is compound, consisting essentially of a frame 36 of transparent material which receives a piece 10 of paper or cardboard 38. This paper or cardboard can bear any desired written matter or form a label. It slides within the frame 36, which is essentially C-shaped. The spring is part of a piece of wire bent to U-shape, the legs 40 and 41 of the U tending to spring apart and so grip the frame 36. Between these legs a length of the wire is bent forwardly to form a handle 42. The leg 40 continues as the spring proper 43 and passes through an opening 44 in the top of the frame.

Figures 8 and 9 show a paper or cardboard strip 45 which is gripped at one end by a piece of sheet metal 47 which is somewhat deeper than the strip. A wire is bent to form a spring 49 and a handle and locating element 50 with two legs 51 and 52 which extend along the edges of the strip. The ends of the metal piece 47 are folded over the legs 51 and 52 to grip the strip and serve to hold these legs in position. This form of strip has the advantage that the greatest wear is resisted by the metal locating element, and a card body is easily printed with various markings if required. Moreover, both this strip and that shown in Figure 7 have locating elements or tongues which are barely visible and so do not detract from the utility of the apparatus in displaying information.

Finally, strips with springs may be used in apparatus in which the channels extend vertically and the strips are moved vertically as the state of affairs to be indicated changes.

I claim:

1. Apparatus for displaying variable information, comprising a frame, a plurality of strips individually movable along said frame in longitudinal overlapping relationship to give a visual representation of information by their exposed parts, means on said frame forming a guide for said strips, locating means along said guide, and, 45 individual to each strip, a locating member connected to said strip and movable in directions parallel to the plane of said strip and perpendicular to the length of said strip to engage

5 with and disengage from said locating means in a plurality of positions of said strip, said locating members being normally positioned out of the path of relative longitudinal movement of the lengths of said strips so that each strip can be moved without disturbing the other overlapping strips, a handle for said locating member, and a spring extending from said strip in a direction parallel to the plane thereof and urging said locating member into engagement with said locating means.

2. Apparatus as claimed in claim 1 wherein said locating member and said handle are parts of a projection rigid with said strip and perpendicular to the plane thereof, and said spring bears against said guide opposite said locating means.

3. Apparatus as claimed in claim 2 wherein said locating means comprises a wall of said 20 guide overlapping the faces of said strips adjacent one edge, said wall being indented to define a series of openings to receive the base of said projection.

4. Apparatus as claimed in claim 2 wherein 25 said spring is of wire secured at one end to said strip, extending obliquely from said strip, and rounded at its other end.

5. Apparatus as claimed in claim 4 wherein 30 said wire spring is clipped to one end of said strip by a bent piece of sheet metal.

6. Apparatus as claimed in claim 1 wherein 35 said locating member and handle are carried by said spring.

7. Apparatus as claimed in claim 1 wherein 40 each of said strips comprises a transparent sheath carrying said spring, and an opaque insert within said sheath.

RAYMOND A. E. GUICHARD.
